UNITED STATES PATENT OFFICE.

GEORGE E. HOYT, OF NEW ORLEANS, LOUISIANA.

JOURNAL-BOX BRASS.

1,130,602.

Specification of Letters Patent.

Patented Mar. 2, 1915.

Application filed April 8, 1913. Serial No. 759,707.

To all whom it may concern:

Be it known that I, GEORGE E. HOYT, a citizen of the United States, residing at New Orleans, in the parish of Orleans and State 5 of Louisiana, have invented new and useful Improvements in Journal-Box Brasses, of which the following is a specification.

This invention relates generally to an improvement in journal boxes and particularly 10 to a specific construction of the bearing surface of the brass therein to minimize friction.

The main object of the present invention 15 is the provision of a brass for the journal box particularly constructed in the arrangement of the Babbitt-metal thereon to materially reduce the bearing surface and consequently minimize the friction.

The invention in its preferred form of 20 details will be described in the following specification, reference being had to the accompanying drawings, in which:

Figure 1 is a bottom plan view of the improved brass. Fig. 2 is a vertical sectional view on the line 2—2 of Fig. 1 with the axle 25 in place. Fig. 3 is a sectional view on the line 3—3 of Fig. 1.

Referring particularly to the accompanying drawings, the brass 1, which aside from 30 the details hereinafter noted, is of the usual construction for coöperation with the ordinary journal box, is materially reduced in width at its central point gradually increasing therefrom to the wheel seat end of the brass. On the surface of the brass adjacent 35 the axle 2 is arranged the Babbitt bearing, the same being secured to the brass in any desired or preferred manner. This Babbitt bearing will, for the sake of clearness of 40 description, be stated to include two strips 3 and 4 intersecting at the central point of the brass and disposed at an angle to each other longitudinally of the brass. The bearing or lower surfaces of the bearing strips 3 and 4 45 are of course curved to conform to the curvature of the axle, and the adjacent ends of the respective strips are spaced apart a distance less than the diameter of the axle. By this arrangement it will be obvious that considering the bearing surface of the axle as 50 circular the Babbitt bearing has its maximum bearing pressure point centrally of the strips from which the bearing extends in opposite directions and in effect on spiral 55 lines, as by reason of the angular relation of the strips they extend spirally of the axle.

Under these conditions a minimum pressure point in bearing is obtained at the remote ends of the strips, and the bearing pressure gradually increases from such minimum point toward the center or juncture of the strips where the maximum pressure is had. 60

If desired, the brass intermediate the adjacent edges of the strips beyond their meeting point may be cut away to reduce the 65 weight, and the ends of the strips at the end of the brass next the flange of the journal box may be connected by a transverse strip 5.

The Babbitt strips 3 and 4 are preferably 70 supplemented by brass strips 5 which are arranged on the sides of the Babbitt strips to support said Babbitt metal from spreading or mashing out. Furthermore, by reason of the formation of the Babbitt which includes the two strips 3 and 4 intersecting at the central point of the brass and disposed at an angle to each other longitudinally thereof, and the end strips 5 provide openings 6 which are arranged medially of the said brass at opposite sides of 75 its center, these openings 6 coincide or register with openings 7 correspondingly shaped thereto and formed in the crown of the brass so that when the brass becomes heated from excessive friction the expansion and contraction resultant will be taken care of due to the openings 6 and 7 in both the Babbitt and crown. Thus it will be seen that the brass by reason of its construction with the openings 6 and 7 permits expansion and contraction thereof under all 80 conditions. 85

What is claimed is:—

1. The combination with a brass for journal boxes, of a Babbitt bearing arranged on 90 the journal side of the brass and having diagonally arranged bearing strips of uniform width throughout disposed in criss-cross relation longitudinally of the brass to the ends thereof and intersecting each other at the central point of the latter to form spaces therebetween at opposite sides of their point of intersection, the surfaces next to the journal of the bearing strips being curved to conform to the curvature of the said journal, 95 and also the adjacent ends of the respective strips being spaced apart a distance less than the diameter of the journal, and pieces connecting the ends adjacent to each other of the respective strips, the said brass having 100 its crown provided with openings correspondingly shaped to and coincident with 105

the spaces formed in the Babbitt bearing by the diagonally arranged strips and end pieces to allow for expansion and contraction of the crown and Babbitt, the width at a point centrally of the intersection of the strips being identical to the width of the longitudinal stretches of the strip beyond the intersection thereof, the inner faces of the strips being in contact throughout their 10 area with the brass.

2. In a brass for journal boxes, a crown piece, and a Babbitt bearing arranged on the

journal side of the crown piece, the said crown piece and Babbitt bearing being formed with coincident openings tapering 15 in a direction toward each other and arranged at opposite sides of the medial portion thereof.

In testimony whereof I affix my signature in presence of two witnesses.

GEORGE E. HOYT.
